TYPEWRITING MACHINE

Henry Allen Avery and Joseph P. Barkdoll,
Groton, N. Y., assignors to L. C. Smith &
Corona Typewriters, Inc., Syracuse, N. Y., a cor-
poration of New York

Application January 29, 1938, Serial No. 187,611

16 Claims. (Cl. 197—138)

The invention relates to improvements in type-writing machines and more particularly to paper-holding bail mechanisms or devices for retaining work pieces in proper relation with the platen for receiving impressions from the types.

The invention has for its principal object to provide an improved paper bail mechanism or device affording efficient control of the paper for typing, introduction of the paper into the machine, and for making erasures.

To the foregoing and other ends which will appear hereinafter, the invention consists in the combinations of elements and devices, arrangements of parts, and features of construction described hereinafter and particularly pointed out in the appended claims.

In the drawing:

Fig. 1 is a fragmentary side elevation, with certain parts broken away, showing the invention embodied in its preferred form and incorporated in a known typewriting machine of the semi-front strike or three-quarter strike variety, the bail being shown in its "on" or working position;

Figs. 2 and 3 are views similar to Fig. 1, but showing the paper bail in two different "off" positions;

Fig. 4 is a front view of the bail mechanism with the parts positioned as in Fig. 1;

Fig. 5 is a sectional view on the line 5—5 of Fig. 4; and

Fig. 6 is a view similar to Fig. 5 showing the illustrated parts differently positioned as more fully hereinafter explained.

Referring to the drawing in which the invention is shown incorporated in a known Corona type-writing machine, 10 designates the traveling platen carriage having end plates 10^a and 10^b, 11 the rotary platen mounted in the carriage, and 12 the carriage bed upon which the carriage travels. In addition to these parts, the known machine also includes type bars which strike upon the upper front portion or quadrant of the platen, one of said type bars being shown in the drawing and designated 13. The improvements will now be described.

The paper bail comprises a metal rod or shaft 14, a pair of sheet metal side arms 15 and 16 connected at their upper ends by said rod, and the usual pair of rubber-faced paper feed rolls 17 rotatively mounted on rod 14. The bail also has a suitable hand knob or finger piece 18 fixed thereto at its right hand end opposite rod 14 and at the outer face of bail side arm 16. The side arms of the bail are pivotally mounted at their lower ends on the carriage end plates by means of

pivot elements 19 and 20 for swinging of the bail into and out of contact with the platen about a horizontal axis extending transversely of the machine. The said axis is located below and forward of the printing line of the machine, and the paper feed rolls of the bail contact the platen above and to the rear of the printing line in the "on" position of the bail. A bail return spring 21 is anchored to the carriage and to side arm 15 of the bail to constantly tend to pull the bail into 10 "on" position and to yieldingly hold the bail in that position, the "on" or paper-clamping position of the bail being shown in Figs. 1 and 5.

Provisions are made (1) for a maximum cast off position of the bail in which rod 14 and the 15 feed rolls 17 thereon are located a considerable distance from the platen forward of the vertical plane of the printing line to permit ready access to typed matter at the printing line for making erasures, in which maximum cast-off position the 20 bail is not latched against return movement but must be held by the typist and from which the bail is free to return to "on" position upon release of the hold of the typist on the bail, and (2) for an intermediate cast off and latched off position 25 of the bail in which the rod 14 and rolls 17 are closely adjacent the platen but spaced therefrom to permit ready introduction and adjustment of paper sheets into the machine by the typist. The intermediate cast off and latched off position of 30 the bail is shown in Fig. 2, and the maximum cast off position of the bail is shown in Fig. 3.

The bail is latchable in the intermediate off position shown in Fig. 2 through the medium of a pivoted latch lever or arm 22 mounted on the 35 carriage and of a stud or pin 23 fixedly held to side arm 15 of the paper bail.

Stud 23 projects outwardly from bail arm 15 above bail pivot 19 through a suitable arcuate clearance slot 24 in carriage end plate 10^a. Latch 40 lever 22 is located at the outer face of end plate 10^a, and said lever is pivotally held at its rear end to said end plate by a suitable pivot element 25 to rock up and down. The latch lever extends forwardly and upwardly from its pivot over the shaft 45 of platen 11 and is normally but yieldingly held drawn down into the position shown in Fig. 5 by means of a pull spring 26 anchored to said lever and to end plate 10^a. An upwardly extending stem 27, formed integrally with the latch lever and extending upward from the upper edge of said lever adjacent the forward end of the lever, is formed at its upper end with an outwardly projecting finger-piece or key 28 and an inwardly projecting stop lug 29. Stop lug 29 normally 50

rests on the upper edge of end plate 10^a of the carriage. Depending from the lower edge of lever 22, forward of the platen shaft and adjacent the free forward end of lever 22, is a latching nose 30 integral with the lever and having downwardly converging forwardly and rearwardly facing cam edges.

In the normal lowered position of the latch lever the nose 30 overlaps slot 24 in end plate 10^a and is in the path of movement of stud 23 on bail arm 15. In the "on" or paper clamping position of the bail shown in Figs. 1, 4 and 5, the stud 23 is behind or in rear of latch nose 30, as shown in Fig. 5. In the latched off intermediate "off" position of the bail, shown in Fig. 2, the stud 23 is engaged against the forward cam edge of the latch nose 30 and the latch holds the bail against return to "on" position by reason of the engagement between said nose 30 and stud 23.

The cam edges of the nose permit camming or lifting of latch 22 by stud 23 to permit said stud to pass said nose when the bail is pulled forward by the typist from the "on" position of the bail, and also when said bail is pushed rearward by the typist from the intermediate and latched "off" position of the bail shown in Fig. 2, but when the bail is merely pulled forward from the "on" position far enough for the nose to drop 30 behind the stud (or slightly farther, as shown in Fig. 6) and is then released by the typist or the pull thereon temporarily relaxed, the force existent at such times in spring 21 tending to restore the bail to "on" position is insufficient to permit stud 23 to cam upward the latch lever and pass the nose on said lever. However, if the typist pulls the bail forward a considerable distance beyond that of Fig. 2 or 6 (as into the full "off" position of Fig. 3) and releases 40 the bail, the bail will receive sufficient return impetus, due to the added stressing of spring 21 and also to bail momentum acquired before stud 23 contacts nose 30, for the stud to force itself automatically past the bail latch nose and permit the bail to automatically assume its "on" position.

To facilitate latching off of the bail in the intermediate "off" position thereof shown in Fig. 2, and also to determine the maximum "off" position of the bail shown in Fig. 3, there is provided a cam and gravity actuated or controlled bail stop or arresting device in the form of a sheet metal link 31 having therein a closed slot 32 which extends generally longitudinally of the link. Said link or stop device 31 is pivotally held at one end thereof to side arm 16 of the bail at a point above the bail pivot 20 by a pivot element 33 to permit the link or stop device to swing edgewise up and down relatively to the bail side arm. There is also provided for cooperation with link 31 an inwardly projecting stud or pin 34 which extends through the closed slot 32 in the link, said stud 34 being so located that in the "on" position of the bail it is close to (but preferably out of contact with) that end of slot 32 adjoining link pivot 33, as shown in Fig. 1. Engagement of said stud 34 with the opposite end of the slot 32 determines the full or maximum "off" position of the bail, as shown in Fig. 3. Gravitational force on the link tends to swing the link downward and forward about pivot 33 toward a pendant position.

To facilitate latching of the bail in the position shown in Fig. 2 and to permit shifting of 75 the bail to its full "off" position from either

said latched off position or the "on" position of the bail, there is formed on one edge of slot 32 of the link 31 (that edge which normally tends to gravitate into contact with stud 34 when the bail is pulled forward) a cam hump or projection 35 rounded or shaped for riding thereof in both directions over stud 34 and located adjacent the end of the slot which is nearest the link pivot 33, and there is formed on the opposite edge of said slot 32 and slightly farther from said link pivot than cam 35 a bail-stopping projection 36, projection 36 having an abrupt bail-stopping edge facing toward the link pivot and converging at the top of the projection with an oppositely facing cam edge of said projection 15 facing generally toward the opposite end of link slot 32.

The described construction of the bail cast-off arresting means comprising link 31 and stud 34 is such that when the typist pulls the bail forward away from the platen into the position shown in Fig. 6 (that is, just far enough, or slightly farther than is necessary, to permit latch nose 30 to drop behind stud 23) cam 35 coacts with stud 34 to throw or flip link 31 upward and rearward into the bail arresting position shown in dotted lines in Fig. 6 in which the abrupt edge of projection 36 is pressed forward against stud 34 and prevents continuation of forward movement of the bail under continued pull on the bail. If the typist, when the bail is arrested in the position shown in Fig. 6, releases the bail it will move slightly rearward into the position shown in Fig. 2 and will be held there by latch 22, and the arresting link 31 will be released by the resultant release of pressure of abrupt edge of projection 36 against stud 34 and gravitate into the position of said link shown in Fig. 2, in which latter position of the link stud 34 is to the rear of cam 35 and clear of projection 36.

It will be obvious, therefore, that the typist may readily cast-off and latch the bail in the position of Fig. 2 and may pull the bail forward from said latched off position into the maximum "off" position of Fig. 3. It will also be obvious that the typist may fully cast off the bail from the "on" position by pulling the bail forward into the arrested position of Fig. 6, then slightly relaxing or reversing the forward pull to permit dropping of link 31, and then again pulling forward on the bail until the forward motion is arrested with the bail in the position shown in Fig. 3 by engagement of stud 34 with the end of slot 32 adjacent the non-pivoted end of link 31. Upon release of the hold of the operator on the bail, after the bail is brought to full "off" position, the cam 35 and projection 36 will ride over stud 34 during return of the bail by spring 21, and the bail return force due to the full stretching of spring 21 and the bail momentum acquired before stud 23 engages nose 30 of the bail latch is such that the stud will cam the latch upward and ride past nose 30 to thereby permit automatic full restoration of the bail from the position shown in Fig. 3 to that shown in Figs. 1, 4 and 5.

Manual release of the bail for restoration by spring 21 from the latched off position of Fig. 2 may be effected either by rearward pressure on 70 the bail or its handle 18 or by upward rocking of latch lever 22 by rearward pressure on finger-piece 28 of said latch lever.

It will be apparent from Figs. 1, 2 and 3 that in the bail positions shown in Figs. 1 and 2 the 75

type bars are operable to print without collision with any part of the bail, including the paper feed rolls 17, but that in the bail position of Fig. 3 such collision (at least with the feed rolls 17) is possible. It will be seen, however, that in the described construction it is impossible for the typist to accidentally leave the bail in the position of Fig. 3 or any other position in which the type bars may collide therewith, thus making it impossible for damage to occur to the types or bail from such a collision. It will also be apparent that the parts may be so designed that the latched off and full "off" positions of the bail may be varied relatively to each other and to the platen from the relative positions shown in the drawing.

What we claim is:

1. In a typewriting machine, the combination of a platen, a manually retractible paper bail mounted for swinging thereof toward and from the platen respectively into and out of paper-pressing relation with the platen, spring means constantly urging said bail toward the platen and normally yieldingly holding said bail in paper-pressing relation with the platen, and means controlled by manual retraction of the bail from its paper pressing relation with the platen to positively arrest such retraction at a predetermined point and controlled by relaxation of the manually applied bail retracting force to permit manual retraction of the bail beyond said predetermined point.

2. In a typewriting machine, the combination of a platen, a manually retractible paper bail mounted for swinging thereof toward and from the platen respectively into and out of paper-pressing relation with the platen, spring means constantly urging said bail toward the platen and normally yieldingly holding said bail in paper-pressing relation with the platen, and means controlled by manual retraction of the bail from its paper-pressing relation with the platen to positively arrest such retraction at a predetermined point and controlled by relaxation of the manually applied bail retracting force to permit manual retraction of the bail beyond said predetermined point, and means controlled by manual retraction of the bail to said predetermined point to prevent return of the bail by said spring means to paper-pressing relation with the platen.

3. In a typewriting machine, the combination of a platen, a manually retractible paper bail mounted for swinging thereof toward and from the platen respectively into and out of paper-pressing relation with the platen, spring means constantly urging said bail toward the platen and normally yieldingly holding said bail in paper-pressing relation with the platen, means controlled by manual retraction of the bail from its paper-pressing relation with the platen to positively arrest such retraction at a predetermined point and controlled by relaxation of the manually applied bail retracting force to permit manual retraction of the bail beyond said predetermined point, and means controlled by manual retraction of the bail to said predetermined point to prevent return of the bail by said spring means to paper-pressing relation with the platen, and controlled by the bail to permit return of the bail by said spring means to paper-pressing relation with the platen upon release of the bail after the manual retraction of the bail beyond said predetermined point.

4. In a typewriting machine, the combination of a platen, a pivotally mounted paper-pressing

bail constantly spring urged toward the platen and manually retractible from paper-pressing relation with the platen, and retraction limiting means for the bail, controlled by the bail to positively stop manual retraction of the bail at first one and then the other of two different predetermined points, at the second of which points the bail is retracted considerably farther from the platen than it is at the first point.

5. In a typewriting machine, the combination of a platen, a pivotally mounted paper-pressing bail constantly spring-urged toward the platen and manually retractible from paper-pressing relation with the platen, means for positively stopping manual retraction of the bail upon retraction of the bail a predetermined maximum distance from the platen and controlled by retraction of the bail a lesser distance from the platen and a slight partial return movement of the bail toward its paper-pressing relation with the platen to first positively stop retraction of said bail and then free the bail for retraction thereof said predetermined maximum distance from the platen.

6. In a typewriting machine, the combination of a platen, a pivotally mounted paper-pressing bail constantly spring urged toward the platen and manually retractible from paper-pressing relation with the platen, and retraction limiting means for the bail, controlled by the bail to positively stop manual retraction of the bail at first one and then the other of two different predetermined points, at the second of which points the bail is retracted considerably farther from the platen than it is at the first point, and detaining means controlled by the bail to permit full return of the bail to paper-pressing position by the constantly exerted spring force upon release of the bail at the second of said points and to prevent such full return of the bail by said spring force upon release of the bail at the first of said points.

7. In a typewriting machine, the combination of a platen, a pivotally mounted paper-pressing bail constantly spring-urged toward the platen and manually retractible from paper-pressing relation with the platen, means for positively stopping manual retraction of the bail upon retraction of the bail a predetermined maximum distance from the platen and controlled by retraction of the bail a lesser distance from the platen and a slight partial return movement of the bail toward its paper-pressing relation with the platen to first positively stop retraction of said bail and then free the bail for retraction thereof said predetermined maximum distance from the platen, and detaining means controlled by retraction of said bail said lesser distance from the platen to permit said partial slight return movement of the bail and to hold the bail against further return movement by the constantly exerted spring force.

8. In a typewriting machine, the combination of a platen, a pivotally mounted paper-pressing bail constantly spring-urged toward the platen and manually retractible from paper-pressing relation with the platen, means for positively stopping manual retraction of the bail upon retraction of the bail a predetermined maximum distance from the platen and controlled by retraction of the bail a lesser distance from the platen and a slight partial return movement of the bail toward its paper-pressing relation with the platen to first positively stop retraction of said bail and then free the bail for retraction

thereof said predetermined maximum distance from the platen, and detaining means controlled by retraction of said bail said lesser distance from the platen to permit said partial slight return movement of the bail and to hold the bail against further return movement by the constantly exerted spring force, said detaining means being conditioned by maximum retraction of the bail to permit full return of the bail by said spring force upon subsequent release of the bail.

9. In a typewriting machine, the combination of a platen, a paper feeding device spring held in paper feeding relation with the platen and manually retractible out of paper feeding relation with the platen, and retraction stopping means for said device automatically conditioned by retractive movement of said device from paper feeding relation with the platen to positively stop retractive movement of said device at a predetermined point and also automatically conditioned by a slight partial return movement of said device from said predetermined point to permit retraction of the device beyond said predetermined point.

10. In a typewriting machine, the combination of a platen, a paper feeding device shiftable into and out of a paper feeding relation with the platen into which it is spring urged and from which it is manually retractible, means automatically conditioned by retraction of said device from its paper feeding relation with the platen to positively stop such retraction at a predetermined point and automatically conditioned by a slight partial restoration of said device to said relation from said point to permit retraction of said device beyond said point, and means automatically conditioned by retraction of said device to said predetermined point to prevent full restoration of said device into paper feeding relation by the spring force exerted on said device except when said device is released after manual retraction beyond said predetermined point.

11. In a typewriting machine, the combination of a platen, a support for the platen, a manually retractible paper-pressing bail mounted on said support for swinging thereof toward and from the platen and constantly spring urged toward the platen, a shiftable bail-retraction stopping element pivotally held to said bail, a fixed bail-retraction stopping element held to said support, and cam means on said first stopping element co-active with the second stopping element upon retraction of the bail to swing said first element about its pivot into a bail-retraction-stopping engagement with the second element from which it is pivotally shiftable by the action of gravity on said first element upon a slight return movement of the bail.

12. In a typewriting machine, the combination of a platen, a support for the platen, a manually retractible paper-pressing bail mounted on said support for swinging thereof toward and from the platen and constantly spring urged toward the platen, a shiftable bail-retraction stopping element pivotally held to said bail, a fixed bail-retraction stopping element held to said support, and cam means on said first stopping element co-active with the second stopping element upon

retraction of the bail to swing said first element about its pivot into a bail-retraction-stopping engagement with the second element from which it is pivotally shiftable by the action of gravity on said first element upon a slight return movement of the bail, and releasable means for detaining the slightly returned bail against further return movement under the influence of the spring force urging the bail toward the platen.

13. In a typewriting machine, the combination of a platen, a support therefor, a manually retractible paper bail pivotally mounted on said support for swinging movement toward and from the platen and constantly spring urged toward the platen, a bail-retraction stopping element pivotally held at one end of the element to the bail to swing transversely of the pivotal axis of the bail, a fixed stopping element on the support, said pivoted stopping element having two abutment means spaced different distances from its pivot to engage said fixed stopping element at different points in retractive movement of the bail to arrest such movement, said pivoted element having cam means engageable with the fixed element during bail retraction to cause stopping engagement between the fixed element and the abutment means nearest the pivot of the pivoted element and to permit bringing of the second abutment means into bail retraction stopping engagement with said fixed element by a partial restoration and greater retraction of the bail.

14. In a typewriting machine, the combination of a platen, a platen carrier, a paper bail pivoted on the carrier to permit retraction of the bail from the platen, and means connecting said bail and platen carrier and controlled by bail movement to positively stop bail retraction at different points.

15. In a typewriting machine, the combination of a platen, a platen carrier, a paper bail pivoted on the carrier to swing about a horizontal axis and constantly spring urged toward the platen, a link pivoted at one end to the bail to swing about a horizontal axis under the influence of gravity and having a pin and slot connection with the platen carrier operative to arrest retraction of the bail from the platen at first one and then the other of two different points and to free the bail for retraction to the farthest one of said points by a slight restoration of the bail from the other one of said points, such freeing of the bail being effected by a pivoted movement of the link under the influence of gravity, and said link being freed for such movement by said slight partial restoration of the bail.

16. In a typewriting machine, the combination of a platen, a platen carrier, a paper bail pivoted on the carrier for retraction from the platen and spring urged toward the platen into paper pressing relation with the platen, means connecting the bail and carrier and controllable by pivotal movements of the bail to positively stop retractive movement of the bail at first one and then the other of two different points, and means for preventing automatic spring restoration of the bail from the first one of said points into paper pressing relation with the platen.

HENRY ALLEN AVERY.

JOSEPH P. BARKDOLL.
